CLAIM

The ornamental design for a flying disc target and simulated golf hole receptacle, as shown and described.

DESCRIPTION

FIG. 1 is a front perspective view of a first embodiment of the flying disc target and simulated golf hole receptacle showing the new design;

FIG. 2 is a front elevational view seen from midway between the 5 and 6 o'clock positions in FIG. 4;

FIG. 3 is an elevational view rotated to the 3 o'clock position in FIG. 4;

FIG. 4 is a top plan view thereof;

FIG. 5 is a bottom plan view thereof;

FIG. 6 is a top perspective view thereof; and,

FIG. 7 is a front perspective view of a second embodiment of the design wherein the modification resides in the removal of the support legs.

Any broken line illustration of environmental structure in the drawings is for illustrative purposes only and forms no part of the claimed design.
